UNITED STATES PATENT OFFICE.

FRANCIS O. WILLIAMS, OF NORTH COHOCTON, NEW YORK.

WHEEL-CULTIVATOR.

SPECIFICATION forming part of Letters Patent No. 250,180, dated November 29, 1881.

Application filed March 7, 1881. (No model.)

To all whom it may concern:

Be it known that I, FRANCIS OSCAR WILLIAMS, of North Cohocton, in the county of Steuben and State of New York, have invented 5 a new Improvement in Wheel-Cultivators, of which the following is a full, clear, and exact description.

The object of my invention is a sulky or wheel-gang cultivator or shovel-plow for tilling corn or potatoes, or anything planted in rows, which shall be light, durable, of easy draft, and one which can be turned around within small space, and can be effectively and easily used upon side-hills.

15 In the accompanying drawings, Figure 1 is a plan view of my improved cultivator. Fig. 2 is a side elevation of the same; and Fig. 3 is a rear elevation, showing a portion of the lever and cross-bar for operating the turning 20 of the wheels.

Similar letters of reference indicate corresponding parts.

The frame is composed of the bars A A', which are secured parallel to each other across 25 the tongue B and at right angles thereto.

The cross-bars C C', which carry the plow-standards D D, may be of metal, and the cross-bars C are adjustable along the parallel bars A A' by means of the bolts passing through 30 the holes a a', formed in the parallel bars, while the cross-bars C' are adjustable at the forward end by bolts passing through the holes a' in the cross-piece A', and at the opposite end through the larger holes, e, in the cross-piece A, as hereinafter described.

35 The wheels E E' are journaled in the bifurcated uprights F F, which pass through the ends of the bar A and through the ends of the cross-bars C' C', and are pivoted therein, and 40 the upper ends thereof are provided with the cranks G G, which are tied together at the top by the bar G'. The tie-bar G' is slotted at g, and is provided at this point with the slotted and notched crown h, through which the lever 45 H, which is pivoted at i to the bar A, passes to operate the wheels for turning and guiding the cultivator, the lever H being retained in any desired position by means of a suitable projection entering the notches in the crown. 50 The wheels E E' are formed with the central rib or sharp projection, e' e', around the pe-

ripheries, which prevent them from slipping when thrown out of line by the lever H.

The plow-standards D D are preferably bent or elbow-shaped, as shown, and are pivoted at 55 d to or in a slot cut through the cross-pieces C C', and they are each formed at their upper ends into a segment, J, which is provided with the adjustment-holes j, through which the long rod K passes. The rod K also passes through 60 the slotted lever L, which is pivoted at l to the side of the tongue B, as shown in Fig. 1, by which means the cultivator or shovel-plow points, as the case may be, may be raised for passing over rocks, irregularities in the ground, 65 or other obstacles, or for turning around at the ends of the rows.

The seat N is bolted to the tongue B by the bolt n, and is adjustable thereon by means of the elongated hole or slot n' in the support N', 70 for the purpose of regulating the same to the weight of the person on the seat, so that his weight will not fall too much upon the necks of the horses.

The plow-points may be set to run deep or 75 shallow by the adjustment of the rod K in the holes j of the segment-shank of the standards; but should it be desired for any cause to raise the points or lower the points still more, the frame may be vertically adjusted upon the up- 80 rights F by means of the washers e e on the shanks of the uprights, which may be taken from above the frame, as shown in the drawings, and placed under it, or vice versa.

The lateral adjustment of the cross-bar C' to 85 suit the cultivator to rows of different widths is accomplished by the large holes c c', formed respectively through the ends of the bar A and cross-bars C' C', by which means the cross-bars may be brought nearer together and the 90 parts secured together by the uprights F, as shown.

It will be observed that by this means the wheels E E' are always behind the plows and always have an even and firm track to run in, 95 and thus never raise the plows from the ground in passing over irregularities, and that by means of the wheels being pivoted and controlled by a lever the same may be set at any angle right or left, which is a great advantage 100 in turning and working upon a side-hill.

Though I have described my invention as a

cultivator or shovel-plow for use for tilling purposes, I may add that it is also adapted for marking out the ground previous to planting, and it may also be used for covering potatoes and for other purposes.

Having thus described my invention, what I claim as new, and desire to secure by Letters Patent, is—

The combination, with a plow-frame composed of the bars A A', slotted adjustable cross-bars C C', and tongue B, carrying the seat N

and lever L, all supported upon the wheels E at the rear of said frame, of the elbow plow-standards D, pivoted at their angles in the slots of the cross-bars, and provided with segments J, having adjusting-holes *j*, and connected by a rod, K, substantially as described, and for the purpose set forth.

FRANCIS OSCAR WILLIAMS.
